UNITED STATES PATENT OFFICE.

IRA WARREN, OF BOSTON, MASSACHUSETTS.

TONSIL INSTRUMENT.

Specification of Letters Patent No. 10,434, dated January 17, 1854.

To all whom it may concern:

Be it known that I, IRA WARREN, of Boston, in the county of Suffolk and State of Massachusetts, have invented a new and useful Improvement in Tonsil Instruments; and I hereby declare the following to be a full, clear, and exact description of the same, reference being had to the annexed drawings, making part of this specification.

10 In follicular and many other throat diseases the tonsils are found enlarged, inflamed and sometimes indurated. In such cases they secrete a thin, unhealthy, irritating fluid which is spread over the throat and increases and perpetuates the disease, which is seldom cured until these diseased tonsils are removed. The instrument heretofore in use for the excision of these enlarged and diseased glands, which was called the 20 "guillotine" though more effective than the means possessed before was liable to several objections. Cutting as it did from one side of the gland to the other, the membranous folds lying about the base of the tonsil, were oftentimes pushed between the plates and left uncut, the tonsil was thus left hanging down the throat, nearly strangling the patient and requiring to be subsequently separated by other means.

30 My invention consists in the employment of two crescent shaped blades, which when opened, leave a sufficient space to allow the tonsil to be drawn between them, and which commence cutting around the whole circumference of the tonsil, and from thence to its center, thus insuring the complete excision of the gland at one operation.

To enable others skilled in the art to make and use my invention I will proceed to describe its construction and operation.

Figure 1 is a representation of the instrument heretofore in use for the purpose, called the guillotine. Fig. 2 is an elevation of the same; Fig. 3, a perspective view of my instrument; Fig. 4, a view of one of the blades with the crescent shaped cutters. Fig. 5 is the lower guard or plate which confines and guides the blades; Fig. 6, the upper guard or confining plate; Fig. 7, the nuts and screws by which the blades and guards are secured together, the pin serving as the pivot by which the tenaculum is made capable of a universal motion.

In Figs. 1 and 2 *a* is the upper, *b* the lower guard. *c* is the knife which is made to slide between the guards and is operated by the

handle *d*. Both the upper and lower guards are terminated by a flat ring *f*, Fig. 1. This end of the instrument was placed over the gland to be cut out and gently pressed until the gland protruded through or into the space within the ring. The knife was then pushed forward, and the portion of the glands above the rings of the guards was separated. It was found however that as the cutting commenced at the base upon one side of the gland, and terminated at the opposite side that the surface membranes, which remained last to be cut instead of being separated were drawn into the space between the knife and guard. This was a serious objection to the instrument, as it often happened that several successive cuts were not sufficient to separate the tonsil entirely from the mouth, and the operation which was thus but imperfectly performed gave both pain and uneasiness to the patient. In the absence of the tenaculum or some means to hold the gland during the operation it frequently occurred that the top of the gland was simply shoved, and the gland itself not being removed was liable to become again enlarged and soon require a repetition of the operation. All these causes of uncertainty and unnecessary pain are avoided in the instrument which I have contrived for the purpose and which is represented in Figs. 3 to 7 inclusive.

The construction and operation of my cutters are peculiar and I believe different from anything heretofore in use for the purpose; they may be described as follows:

g are the body of the blades which are pivoted at *e* in a manner similar to that in which scissor blades are hung.

k are the handles and *h* the crescent shaped cutters.

i Fig. 5 is the lower guard having side flanges *l* and projecting lips *m*.

n Fig. 6, is the upper guard which is slid beneath the lips *m* of the lower guard. These guards are both furnished with oval openings *o o'* and are secured above and below the cutting blades by the screw *p* Fig. 7 which serves as the pivot upon which the blades turn.

The crescentic cutters *h* when opened are concealed between the guards, the flanges *l* limiting their motion in this direction. In the act of closing they pass each other as seen in Fig. 3 and sever whatever is between them. The pivot *p* is also made the socket

of a smaller shaft or pin *v* which serves to secure the forceps represented in Fig. 3 to the instrument; these forceps are furnished with handles *s* and claws *t*, the operation of which will be presently described, by virtue of the combined movement of the forceps upon the pivot *p* and pin *v*, they are rendered capable of a universal motion around their point of attachment to the instrument.

- 10 Operation: The tenaculum or forceps being secured to the body of the instrument as described the blades are opened so that they lie concealed between the upper and lower guard plates—the rings *o o'* are then pressed 15 slightly upon the tonsil which is seized by the claws *t* of the tenaculum by which it is drawn sufficiently far through the rings of the guard plates and held firmly: the crescentic blades are then closed and the gland 20 is instantly removed.

As before stated where the old instrument is used the membranous folds at the base of the gland upon the side opposite to that upon which the cutting commences are the

last to be cut, from which result the disagreeable consequences before enumerated. Where the cutting commences as it does in my instrument all around the base of the gland, these membranes are separated at the commencement of the operation and the 25 tonsil is instantaneously and easily removed.

Should the gland from any cause be without the reach of the tenaculum when the latter is secured to the instrument as represented in Fig. 3, the pin *v* may be withdrawn, the tenaculum may then be passed through the rings *o o'* and the tonsil may 30 thus be seized and drawn up to the cutters.

What I claim as my invention, in an instrument for the excision of the tonsils, and 35 other analogous operations, is—

The crescent shaped blades, constructed and operating in a manner substantially as described, and for the purposes set forth.

IRA WARREN.
